(57) **CLAIM**

The ornamental design for a T-post adapter bracket, as shown and described.

DESCRIPTION

FIG. 1 is a top perspective view of a T-post adapter bracket showing my new design;

FIG. 2 is a top plan view of the T-post adapter bracket, it being understood that the bottom plan view is a mirror image thereof;

FIG. 3 is a front elevation view of the T-post adapter bracket;
FIG. 4 is a rear elevation view of the T-post adapter bracket;
and,

FIG. 5 is a side elevation view of the T-post adapter bracket, it being understood that the opposite side elevation view is a mirror image thereof.

The elements shown in broken lines are for illustrative purposes only and form no part of the claimed design.
